UNITED STATES PATENT OFFICE.

HARRY H. VICKERS, OF CORONA, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed February 20, 1923. Serial No. 620,167.

To all whom it may concern:

Be it known that I, HARRY H. VICKERS, a citizen of the United States, residing in Corona, Long Island, in the county of Queens and State of New York, have invented certain new and useful Improvements in Typewriting Machines, of which the following is a specification.

The invention relates to tables on the carriage of a typewriting machine for guiding work-sheets to the platen. More particularly, the invention relates to machines in which two tables are provided, one spaced forward of the other at the rear of the platen; the tables being employed concurrently, and the sheets from one table being superposed at or near the platen upon the sheet or sheets from the other table. The occasion for such independent feed of work-sheets to the platen ordinarily arises where it is desired to use, and to retain in the machine, a record-sheet on which to accumulate the entries made on a succession of individual bill or statement sheets. In this use of the tables, the record-sheet is fed from the forward table, and the individual statement-sheets from the rearmost table; the collation and feed of the sheets, in the machine, being explained in the pending application of Jesse A. B. Smith, Serial No. 598,066, filed October 31, 1922, now Patent No. 1,524,756, dated February 3, 1925, to which reference is made for details not herein shown.

A feature of the present invention is the provision of means for supporting the tables for adjustment independently one of the other.

A further feature of the invention is the provision of means whereby the record sheet or sheets, on the forward table, may be supported against the platen or prevented from sagging into the path of the sheets being introduced from the platen from the rearmost table; thus allowing free and unobstructed movement under and around the platen of the sheets from the rearmost table, and preventing dragging of the stationary record-sheet by the sheets advancing from the rearmost table.

In the preferred embodiment thereof, the invention comprises means for adjusting the forward table to bring the lower or delivery edge thereof into such position, or close proximity to the platen, as to exert a drag

on the record-sheet when the latter is fed with, or advanced around, the platen; and thereby to cause the record-sheet, after such feed, to be held up frictionally by such lower edge, or equivalent lip, between the same and the platen, out of the way of the sheets from the other table; this result being aided by rolls running on the record-sheet at the delivery side of the platen, and the stationary record-sheet being caused to hug the stationary platen between said lip and said rolls, and hence to leave the path constantly clear for the statement to be introduced from the rear and thrust forwardly under and up around the stationary platen preparatory to typing upon both sheets.

A feature of the invention, in the preferred form thereof, is the independent support and adjustability of the forward table, or delivery lip thereon, both forward and rearward, and up and down, with respect to the platen.

The adjustability may be made to accord to varying thicknesses of paper on the forward table, without regard to a fixed operative setting of the rearmost table.

Other features and advantages will hereinafter appear.

In the accompanying drawings, Figure 1 is a view, in front elevation, of the platen-carriage of an Underwood typewriting machine having thereon the paper-table of the present invention.

Figure 2 is a view, in side elevation, taken on the line 2—2 of Figure 1.

Figure 3 is a perspective view, showing the right-hand end of the platen-carriage and of the paper-table, and the bracket by means of which the table is adjustably mounted on the ends of the platen-carriage; the parts being separated for clearer illustration thereof.

The platen 10 is journaled by means of its axle 11 in side plates 12 of the carriage, supported, in part, by rail 13 for movement in letter-feed and return directions on the main frame 14 of the machine. The platen-shaft 11 is provided with the usual hand-wheels 14^a and line-space mechanism 15; the latter not being fully shown, but being of the kind found on the Underwood machine.

The side plates 12 of the platen-carriage are connected and tied together by a cross-piece 16 at the rear of the platen, and fast to this cross-piece is the usual paper table 17.

- and apron 17, for guiding the paper around underneath the platen to the front thereof. Front and rear pressure-feed-rolls 18 and 19, respectively, are indicated below the platen.
- 5 These rolls, normally bearing upon the platen, are adapted to be thrown off the platen, or released, for free movement of the paper around the platen, by mechanism not shown, but which may be of the kind found 10 in the Underwood typewriting machine.

The rear paper-table 20 is connected at 21 to the rear table-extension of the apron 17. Connection 21 may be a pivotal connection, so that, when desired, the table 20 may be 15 swung. To provide the pivotal connection 21, ears 22 are turned or curled out of the body of the table-extension of the apron 17, and carry pins on which ears 23, similarly turned or curled out of the body of the table, 20 are journaled. The table 20 is, however, normally held stationary on the platen-carriage against movement on its pivot 21; and, for so holding the table 20, it is secured by 25 thumb-screws 24, one at each side thereof, to brackets 25, in turn, secured by screws 26 to the side plates 12 of the platen-carriage.

Mounted independently on the platen-carriage, forward of the table 20, is another table 27. The table 27 is secured by screws 30 28 to ears 29 on brackets 30, in turn, secured by screws 31 to the side plates or ends 12 of the platen-frame or carriage. In order that the table 27 may be adjusted up and down on the brackets 30, it is slotted at 32 where 35 the screws 28 pass therethrough. The screws 28 thread into the bracket-ears 29, and, when turned home, the heads of the screws bear against the table 27 and hold the same in adjusted position. The table 27 is also ad- 40 justable forward and rearward with respect to the platen, and, to this end, the brackets 30 are slotted at 33 where they receive the screws 31. The screws 31 are threaded into the carriage-plates 12, and, when the screws 45 are turned home, the heads thereof bear on the brackets 30 and hold the same in ad- justed position.

As fully explained in the hereinbefore-mentioned application of Smith, the table 50 27 is employed as a guide and support for a record-sheet, or other sheet on which the several entries made on the individual statement-sheets, fed down over the rear table 20, are successively entered. Such a record- 55 sheet, indicated at 34, is shown as led between the lower end 35 of the table 27 and the platen, thence around the platen, across the printing line, and up between the platen and paper-finger-rolls 36 to the rear of a 60 front collating table 37. A carbon-sheet 38 is shown as accompanying the record-sheet. To provide for free passage of the record-sheet behind the collating table and paper-finger-rolls 36, and to permit of adjustment 65 of the record-sheet, freely on the platen,

after completion of the entries on the individual statements, the lower end of the collating table 37 and paper-finger-rolls 36 are adapted to be swung forward. For this purpose, the collating table, which is in two sections 37^a and 37^b, is secured to a bail 39, fast on a rock-shaft 40, journaled in brackets 41, secured by screws 42 to the side plates 12 of the carriage. The paper-fingers which carry the rolls 36 are not shown, but may be 70 of the structure shown in the aforesaid Smith application, and, as therein shown, are connected to the rockshaft 40 to move therewith. Fast to the left-hand end of the shaft 40 is a finger-piece 43 by means of 75 which the shaft may be rocked to swing the collating table and paper-finger-rolls. The collating table is in two sections, adjustable relatively to each other, longitudinally of the platen, by means of slots 44 and screws 80 45, to accommodate itself to sheets of different widths; and the sections 37^a and 37^b of the collating table have flanges or side gages 46 for the papers on the collating 85 table.

The record-sheet table 27 is adjustable so closely to the platen that the record-sheet will drag on the lower edge 35 of the table 27; the object being to prevent dropping or sagging of the stationary record-sheet 90 away from the platen. Instead of a single sheet 34, there may be several sheets led over the table 27, and adjustment of the table, to accord to the thicknesses of paper 95 between the edge 35 thereof and the platen, 100 may also be required.

The sheet or sheets 34 on the table 27 being held up, as described, by the edge 35 of the table, and the pressure-rolls 18 and 19 being released, the sheets on the rear 105 table 20 may be passed freely around under the platen, unobstructed by the sheets 34, and without dragging, pushing or bulging the sheets 34 forward, and may thence be drawn to the collating table 37, and collated 110 thereon. The steps involved in the adjustments of the record-sheets, and in the collating operation, are well understood, and, in any event, are explained in the aforesaid 115 Smith application.

Variations may be resorted to within the scope of the invention, and portions of the improvements may be used without others.

Having thus described my invention, I claim:

1. In a typewriting machine, a platen, a platen carriage, two tables at the rear of the platen, one spaced forward of the other, for guiding work-sheets down to the platen, the forward table being normally secured 125 in a fixed position and having a lip adjacent the platen for supporting the sheet on the forward table out of the path of the sheet on the rearmost table, and means settable for adjusting said forward table in 130

other fixed positions relatively to the platen, for varying permanently the width of the sheet-opening between the lip and the platen.

5. 2. In a typewriting machine, a platen, a platen carriage, two tables at the rear of the platen, one spaced forward of the other, for guiding work-sheets down to the platen, the forward table having a lip adjacent the platen for supporting the sheet on the forward table out of the path of the sheet on the rearmost table, means for adjusting the lip forward and rearward relatively to the platen, and independent means for adjusting

15 the lip up and down relatively to the platen.

3. In a typewriting machine, a platen, a platen carriage, two tables at the rear of the platen, one spaced forward of the other, for guiding work-sheets down to the platen, 20 the forward table having a lip adjacent the platen for supporting the sheet on the forward table out of the path of the sheet on the rearmost table, brackets on the carriage for supporting the forward table, and means 25 for adjusting the position of the brackets on the carriage to adjust the lip relatively to the platen and to the rearmost table.

4. In a typewriting machine, a platen, a platen carriage, two tables at the rear of the platen, one spaced forward of the other, for guiding work-sheets down to the platen, the forward table having a lip adjacent the platen for supporting the sheet on the for-

ward table out of the path of the sheet on the rearmost table, and means for adjusting 35 the lip relatively to the platen and to the rearmost table.

5. In a typewriting machine, a platen, a platen carriage, two tables at the rear of the platen, one spaced forward of the other, 40 for guiding work-sheets down to the platen, the forward table having a lip adjacent the platen for supporting the sheet on the forward table out of the path of the sheet on the rearmost table, brackets on the carriage 45 for supporting the forward table, and means for adjusting the position of the forward table on the brackets to adjust the lip relatively to the platen and to the rear- 50 most table.

6. In a typewriting machine, a platen, a platen carriage, two tables at the rear of the platen, one spaced forward of the other, for guiding work-sheets down to the platen, the forward table having a lip adjacent the 55 platen for supporting the sheet on the forward table out of the path of the sheet on the rearmost table, brackets on the carriage for supporting the forward table, and means for adjusting the position of the forward table on the brackets and of the brackets on the carriage to adjust the lip up and down, and forward and rearward, 60 relatively to the platen and to the rearmost table.

HARRY H. VICKERS.
